MULTICOLOR PRINTING MACHINE

Frederick Lamatsch, Grantwood, N. J., assignor
to R. Hoe & Co., Inc., New York, N. Y., a cor-
poration of New York

Application August 30, 1941, Serial No. 409,094

6 Claims. (Cl. 270—5)

This invention relates to printing machines, and more particularly to rotary multicolor web printing machines constructed and arranged for maximum flexibility in operation and choice of web runs.

Various constructions and arrangements of printing units have heretofore been provided to produce multicolor products. In some of these arrangements there is provided a common impression cylinder having a number of plate or form cylinders disposed in cooperable relation therearound. In others, a plurality of superposed color printing units are provided, and they are arranged to permit various web runs. A number of other arrangements are provided, but in each instance, the operating and web run flexibility have definite limitations. More recently, standard perfecting newspaper units with additional printing cylinders have been employed to produce multicolor printing, but although such arrangements are relatively satisfactory, they, too, lack the operating and web run flexibility now commercially desired.

An object of this invention is to provide a printing machine incorporating a folder and a plurality of rotary printing units in line, certain of the units being standard perfecting units and others having standard components provided with a plurality of color printing couples, the construction and arrangement being such as to afford maximum operating flexibility and choice of web runs.

Another object of this invention is to provide a rotary printing machine incorporating a folder and a group of printing units in line, the group including two standard rotary perfecting units, and a unit interposed therebetween which incorporates four printing couples.

An additional object of this invention is to provide a rotary printing machine incorporating a plurality of folders and a plurality of groups of printing units, each group being located between adjacent folders, and including two standard rotary perfecting units and another unit interposed therebetween and incorporating four printing couples.

A specific object of this invention is to provide a rotary printing machine incorporating a folder and a group of three printing units in line, to provide outside units and an intermediate unit, the end or outside units in the group being standard rotary perfecting printing units, and the intermediate unit incorporating four printing couples so positioned that two printing couples are arranged in vertical alignment relative to the other two printing couples.

It is also an object of this invention to provide a rotary multicolor web printing machine of generally improved construction and arrangement whereby the device will be simple, durable and inexpensive in construction, as well as convenient, practical, serviceable and efficient in its use.

With the foregoing and other objects in view, which will appear as the description proceeds, the invention resides in the combination and arrangement of parts, and in the details of construction hereinafter described and claimed, it being understood that various changes in form, proportion and minor details of construction may be made within the scope of the claims without departing from the spirit or sacrificing any advantages of the invention.

For a complete disclosure of the invention, a detailed description thereof will now be given in connection with the accompanying drawings forming a part of the specification, wherein:

Figure 1 is a diagrammatic side elevation depicting a plurality of folders and printing units in line, certain of the units being arranged in an operative group, the web run arrangement being such as to produce three black perfected webs;

Figure 2 is a similar view, but depicting the webs as being run through the units to produce one web with black on the inside and four colors on the outside of the product, and also a black perfected web;

Figure 3 is a similar view, but depicting the webs as being run to produce a black perfected web, and a color web similar to that produced in the arrangement of Figure 2, but with the four colors printed on the inner side of the outside sheet of the product;

Figure 4 is a similar view, but depicting two webs as being so run that one web is perfected in black, and the other having black on one side, and four colors on the other, with the colors being disposed on the inner side of the inner sheet of the product;

Figure 5 is a similar view, but depicting the webs as being so run that the color web is placed on the outer side of the inner sheet of the product;

Figure 6 is a similar view, but depicting the webs being so run through the units and to the folder as to produce two webs having black on one side and three colors on the other, the color printing being on the outer side of the outside sheet and the inner side of the inside sheet in each product;

Figure 7 is a similar view, showing an arrangement for producing two webs having the same number of colors on each web as produced by the arrangement depicted in Figure 6, but

with the colors reversed, the color printing being on the inner side of the outside sheet and the outer side of the inside sheet in each product;

Figure 8 is a diagrammatic side elevation of a group of units depicting a preferred drive arrangement;

Figure 9 is a diagrammatic view similar to Figure 1, the web run arrangement being such as to produce two webs perfected in black and a third web printed in three colors on one side, and black on the other; and

Figure 10 is a side elevation of a line of printing units and a folder, as shown in Figures 1 to 9, but depicting a portion of the line that includes a folder with a group of three units on each side thereof and with turner bars and slitters, the web runs shown being such as to print one web with four colors on each side, one web with two colors on each side, and to perfect two webs in black.

Referring to the drawings, in which similar reference characters designate corresponding parts, there is depicted an improved printing machine which includes a plurality of standard perfecting printing units and a plurality of four-impression printing units and folders arranged in line. The arrangement is such that three printing units are positioned between adjacent folders, and the three units form a group of units.

Each group includes two perfecting newspaper printing units A and B, and a four-impression printing unit C, located in line therebetween.

The perfecting unit A of each group of units includes two printing couples 11 and 12, and the couple 11 includes an impression cylinder 13 and a plate or form cylinder 15, and the couple 12 includes an impression cylinder 13a and a plate or form cylinder 15a. The perfecting unit B of each group of units includes two printing couples 16 and 17 of standard construction. The printing couple 16 includes the usual impression cylinder 13 and the usual plate or form cylinder 15, and the printing couple 17 includes the conventional impression cylinder 13a and cooperating form cylinder 15a.

The printing units A and B incorporate the conventional inking mechanism for the plate or form cylinders, and also a suitable drive mechanism, the drive mechanism is, however, so constructed and arranged that the cylinders of printing couple 11 in unit A, and the printing couple 17 in unit B are reversibly driven. The inking mechanism is of standard construction well understood by those skilled in the art, consequently, the inking mechanism has not been illustrated in the drawings of this application.

The four-impression unit C incorporates four printing couples 18, 20, 21 and 22. The printing couple 18 includes an impression cylinder 13 and a cooperating form or plate cylinder 15, and the printing couple 20 includes an impression cylinder 13a and a cooperating plate or form cylinder 15a. Located immediately above the printing couple 18 is the third printing couple 21, which includes an impression cylinder 25 and a plate or form cylinder 26. The printing couple 22 is located above the printing couple 20, and the couple 22 includes an impression cylinder 25a and a plate or form cylinder 26a. Preferably all of the printing cylinders of unit C are arranged to be reversibly driven.

A preferred arrangement for imparting power to the printing cylinders is disclosed in the diagrammatic Figure 8, and includes a line shaft 75

L which drives a plurality of vertical shafts V, through meshing bevel gears 23 and 24. A vertical shaft V is provided for each of the perfecting printing units A and B, and two vertical shafts are provided for the four-impression printing unit C. Means for reversing couple 11 of unit A and couple 17 of unit B is provided, and is preferably that shown in Figures 1 to 4 of Lamatsch Patent No. 2,102,631, but it will be understood that all of the printing couples of these units may be made reversible, if desired, by the use of two oppositely positioned bevelled gears 23 on the shaft L, either of which may be slipped into engagement with the gear 24.

15 The vertical shafts V of unit C are each geared directly to the two printing couples which they drive by bevel gearing, a pair of slip gears 31 being provided on the shafts V for each couple and arranged so that either slip gear may be thrown into mesh with their mating gear on the cylinder in accordance with practice well known in this art.

20 Each group of printing units A, B and C is located between adjacent folders 27 and 28, as indicated in the drawings. The folders are preferably of the usual double construction, each having two formers 30 over which the web passes to produce the longitudinal fold in conformity with the usual practice well understood by those skilled in the art. Any preferred number of folders and groups of printing units may be arranged in line. Where a small product is to be produced, a single group of units may be used with a folder 27, or where larger products are 25 to be produced, units in other groups of units may be connected to operate with the first group. As stated, each group of units includes two standard perfecting units, one of the printing couples of each preferably having reversible cylinders, and a four-impression printing unit located between the standard perfecting units, all of the cylinders of the four-impression unit preferably being reversibly driven.

25 In the web run arrangement depicted in Figure 1, the inner web W, that is, the inner or lower web which passes down over the formers 30 of the folder 27, is directed by guide rollers 32 through the printing couples 17 and 16 of unit B, where the web is perfected in black. This web W is then guided by rollers 33 to the drag roller 35 of the folder 27, where it is slit by the conventional slitter disc 34, in conformity with the usual practice, and then led down over the formers 30 of the folder 27, in the manner well understood by those skilled in the art. The second inner web W1, that is, the second web from the formers as it passes down thereover, is led around guide rollers 36 through the printing couples 20 and 18 of the printing unit C, where the web is perfected in black. After the web passes through the printing couple 18, it is led around guide rollers 37 and over the drag roller 35, where it is slit into narrower webs or ribbons, and these ribbons are then directed down over the formers 30 of the folder 27, in conformity with the usual practice.

30 A web W2 is led around guide rollers 38 through the printing couples 12 and 11 of unit A, where the web is perfected in black. After the web W2 passes through the printing unit A, it is led around a guide roller 40 to the drag roller 35, where it is slit into narrower webs or ribbons, and the ribbons or webs are led down over the formers 30 of the folder 27. As the webs or ribbons W2 pass down over the formers 30 of the folder

27, they are the outermost or third webs from the former surfaces.

By this arrangement, three webs are perfected by the printing units A and B, and the printing couples 18 and 20 of unit C.

In the web run arrangement depicted in Figure 2, a web W3 is led around guide rollers 32 through the printing couples 16 and 17 of printing unit B, where the web is perfected in black. After passing through the printing unit B, the web W3 passes around guide rollers 41 to the drag roller 35. This web is then slit into ribbons, and the ribbons passed down over the formers 30 of the folder 27. As the ribbons of the web W3 pass down over the formers, they are located immediately adjacent the formers and thus provide the innermost or lower webs or ribbons.

A web W4 is led around a guide roller 38 to the printing couple 12 of the printing unit A, where a black impression is printed on the first or obverse side of the web. After the web W4 passes through the printing couple 12, it is led around guide rollers 39 and 42, to and through the printing couples 22, 20, 18 and 21 of the four impression printing unit C, where four color impressions are printed on the second or reverse side of the web. After the web W4 passes through the printing unit C, it is guided by rollers 43 to the drag roller 35, where it is slit into webs or ribbons, and these webs are led down over the formers 30 of the folder 27 in the top or outermost position.

By this arrangement, the inner webs which pass down over the formers have both surfaces printed in black, and the outer webs which pass down over the formers have four colors on their outer surfaces indicated 4C in Figure 2, and black on their inner surfaces.

In the web run arrangement depicted in Figure 3, a web W5 is guided by rollers 32 through the printing couples 16 and 17 of the printing unit B, where the web is perfected in black. After passing through the printing unit B, web W5 is guided by rollers 45 to the drag roller 35, where the web is slit into narrower webs or ribbons, and these webs are guided down over the formers 30 of folder 27 so that they provide the inner or lower webs.

A web W6 is guided by rollers 38 through the printing couple 11 of the printing unit A, where a black impression is printed on the first or obverse side of the web. After passing through the printing couple 11, web W6 is guided by rollers 46 and 36 to and through the printing couples 21, 18, 20 and 22 of the four-impression printing unit C, where four colors are printed on the second or reverse side of this web. After passing through the four-impression printing unit C, web W6 is guided by rollers 47 to the drag roller 35, where it is slit into ribbons or narrow webs, and these webs are then led down over the formers 30 of the folder 27 and form the outer or top webs.

In this printing arrangement, the inner webs which pass down over the formers 30 are perfected in black, and the outer webs have four-color impressions on the inside of each outer web, indicated 4C in Figure 3, and a black impression on the reverse side.

In the arrangement depicted in Figure 4, a web W7 is led by guide rollers 32 through the printing couple 16 of printing unit B, where a black impression is printed on the first or obverse side of the web. After web W7 passes

through the printing couple 16, it is then guided around rollers 46 and 36 to and through the printing couples 21, 18, 20 and 22 of the four-impression printing unit C, where four-color impressions are imprinted on the second or reverse side of the web. After web W7 passes through the four-impression printing unit C, it is guided around rollers 48 to the drag roller 35, where it is slit into narrow webs or ribbons which pass down over the formers 30 of the folder 27 to provide the inner or lower webs.

A web W8 is guided by rollers 38 through the printing couples 12 and 11 of the printing unit A, where the web is perfected in black. After the web W8 passes through the printing unit A, it is guided by rollers 50 to the drag roller 35, where it is slit into narrower webs or ribbons, and these webs pass down over the formers 30 of the folder 27 to form the outer or top webs.

In this arrangement, the outer webs which pass down over the formers 30 are perfected in black, and the inner webs have four colors on the inside, indicated 4C in Figure 4, and black on the other side.

In the arrangement illustrated in Figure 5, a web W9 is led by guide rollers 32 through the printing couple 17 of printing unit B, where a black impression is printed on the first or obverse side of the web. After web W9 passes through the printing couple 17, it is led by guide rollers 52 and 36 to and through the printing couples 22, 20, 18 and 21 of the four-impression printing unit C, where four colors are printed on the second or reverse side of this web. After web W9 passes through the printing unit C, it is guided by rollers 53 to the drag roller 35, where it is slit into narrower webs or ribbons and these webs are led down the formers 30 of the folder 27 so that they form the inner or lower webs.

A web W10 is guided by rollers 38 through the printing couples 12 and 11 of the printing unit A, where the web is perfected in black. After web W10 passes through the printing unit A, it is guided by rollers 55 to the drag roller 35, where it is slit into narrower webs or ribbons, and these webs pass down over the formers 30 to form the outer webs.

By this web run arrangement, the innermost webs which pass down over the formers 30, are printed with four colors on their outer or upper surfaces, indicated 4C in Figure 5, and black on their lower or inner surfaces, and webs W10 have black on both surfaces.

In the arrangement depicted in Figure 6, a web W11 is led by guide rollers 32 through the printing couples 16 and 17 of the printing unit B, where black is printed on the first or obverse side of the web, and a color impression is printed on the second or reverse side of the web. After the web W11 passes through the printing unit B, it is guided by rollers 56 to and through the printing couples 20 and 22 of the four-impression printing unit C, where two-color impressions are printed on the second or reverse side of the web. The web W11 is then guided by rollers 57 to the drag roller 35, where it is slit into narrower webs or ribbons which are led down over the formers 30 of the folder 27 to form the inner or lower webs.

A web W12 is led by rollers 38 through the printing unit A, where a black impression is printed on the first or obverse side of the web, and a color impression is printed on the second or reverse side of the web. After web W12 passes through the printing unit A, it is guided

by rollers 58 to and through printing couples 18 and 21 of the four-impression printing unit C, where two additional color impressions are printed on the second or reverse side of the web. Web W12 is then led around guide rollers 60 to the drag rollers 35 where it is slit into narrower webs or ribbons and passed down over the formers 30 to form the outer or upper webs.

By this web run arrangement, three colors are printed on the lower or inner sides of the inner webs and black is printed on the upper or outer sides thereof. Three colors are also printed on the outside or upper surfaces of the outer or upper webs, with black impressions on their lower or inner surfaces, so that the black impressions of the two webs are folded face to face. The surfaces of the webs printed in three colors are indicated 3C in Figure 6.

In the arrangement depicted in Figure 7, a web W13 is led by rollers 32 to and through the printing couples 17 and 16 of the printing unit B, where black is printed on the first or obverse side of the web, and a color impression is printed on its second or reverse side. After web W13 passes through the printing unit B, it is guided by rollers 61 to and through the printing couples 22 and 20 of the four-impression printing units C, where two additional color impressions are printed on the second or reverse side of the web. After web W13 passes through the printing couples 22 and 20 of the unit C, it is guided by rollers 62 to the drag roller 35, where it is slit into narrower webs or ribbons which pass down over the formers 30 of the folder 27 to form the lower or inner webs.

A web W14 is guided by rollers 38 through the printing couples 11 and 12 of the printing unit A, where black is printed on the first or obverse side of the web, and a color impression is printed on the second or reverse side of the web. After web W14 passes through the printing unit A, it is guided by rollers 63 to and through printing couples 21 and 18 of the printing unit C, where two additional colors are printed on the second or reverse side of the web. This web is then led by guide roller 65 to the drag roller 35, where it is slit into narrower webs or ribbons which pass down over the formers 30 to form the outer or upper webs.

By this web run, the inner or lower webs which pass down over the formers 30 have three colors on their upper sides and black on their lower sides, while the outer or upper webs have three colors on their inner or lower sides, and black on their upper or outer surfaces. The surfaces printed in three colors are indicated 3C in Figure 7.

Referring to Figures 6 and 7, it is manifest that two other web runs can be conveniently obtained by using, in one instance, the web run of W12 of Figure 6 with the web run W13 of Figure 7; and, in the other case, the web run W11 of Figure 6 with the web W14 of Figure 7.

In the arrangement depicted in Figure 9, the inside web W15 is directed by guide rollers 32 through the printing couples 17 and 16 of unit B, where the web is perfected in black, and it is then guided by rollers 33 to the drag roller 35 of the folder 27.

The outside web W16 is guided by rollers 38 through the printing couples 12 and 11 of the printing unit A, where the web is perfected in black, and it is then guided by a roller 40 to the drag roller 35.

A third web W17 is led around guide rollers

66 and 67 to and through printing couple 22 of unit C, where it is printed in black on one side, and thence in succession it is led to and through couples 20, 18 and 21 of that unit to receive three colors on the opposite side 3C, as indicated. It is then led around guide rollers 43 to the drag roller 35. It will be observed that this arrangement produces two webs printed in black on each side, and one web printed in black on one side and three colors on the side 3C. It is obvious that by reversing the lead of the web W17 through the unit C so that it is carried first upward through couple 21, then downward through couple 18, and then upward through couples 20 and 22, that it may be printed with three colors on the opposite side instead.

It will be understood that in a press of this kind, it is customary to provide a considerable number of web guide rollers, arranged so as to provide for any desired web run, the web being led around only such rollers as are required to direct it to the desired places, and also that detachable brackets for supporting the bearings of the guide rollers may be employed, which can be easily shifted from one portion of the press frame to another, to locate the roller in any one of a number of positions, and where it can best be used.

The products hereinbefore described are those produced by double folders, where the sheets are run direct to the folder and not slit until they reach the formers. Obviously, by slitting the webs and turning certain of the resulting ribbons to bring them all over one former, various assemblies of these ribbons are selectively permissible, and makes possible a wide choice of products, as is well known to those skilled in the art. Again, when tabloid papers are produced, the additional fold further increases the possible disposition of the color pages, as is generally known in the art.

In Figure 10, slitters and turner bars are shown, and an arrangement whereby webs are led to a folder from units located at each side. A web W18 is led about guide rollers 68 to and through couples 11 and 12 of unit AA, where it receives two colors on a first side, and thence about guide rollers 69, to and through couples 18 and 21 of unit CC, where it receives two additional colors on the first side. It is then led about guide rollers 71 to and through couples 22 and 20 of this unit, where it receives two colors on the second side. It is then led around guide rollers 72 to and through couples 16 and 17 of unit BB, where it receives two additional colors on the second side, and it is then led around guide rollers 73 and 74 to a drag roller 75, where it is slit by a slitter 76, one of the ribbons thus produced being led around guide rollers 77 to the drag roller 35 at the former 30 of the folder, while the other ribbon is passed around turner bars 78, which superimpose it over and align it with the first mentioned ribbon, and it is then carried around guide roller 79 to the drag roller 35, thus producing two ribbons or half width webs printed in four colors on each side, the outer one of which will be the outside page of the product when it is delivered from the folder.

A web W19 is led around guide rollers 32 and successively through couples 17 and 16 of unit B, where it is perfected in black or one color on each side, and thence around a guide roller 81 to a drag roller 82, from whence it may be run without slitting, around guide rollers 83 to the

drag roller 35 over the former, or it may be slit by the slitter 84, and one of the ribbons or half webs carried around the turner bars 85 and guide rollers 86 to the drag roller 35.

Similarly, a web W20 is carried around rollers 38 through printing couples 12 and 11 of unit A, where it is perfected in black, thence around guide rollers 87 to the drag roller 88, where it may be slit and turned, or forwarded without slitting to the drag roller 35 of the former 30.

Another web W21 is led around guide roller 66, through printing couples 20 and 22 of unit C, receiving two colors on one side, and it is then led around guide roller 89, and through couples 18 and 21 of that unit, where it receives two colors on the opposite side, and it is then led around guide roller 91 to drag roller 92, where it is either slit into half width webs, one of which is turned to bring them into alignment before being led to the folder, or the web may be led without slitting to the drag roller 35.

With the leads shown in Figure 10, the web W18 will have four colors printed on each side as indicated 4C, webs W19 and W20 will be perfected in black, and the web W21 will be printed in two colors on each side, as indicated 2C.

From the foregoing, it is manifest that the construction and arrangement disclosed in this invention provides maximum convenience and flexibility in operation, because any selected web may be run through any selected printing unit or selected printing couple thereof, or any combination of printing units and printing couples, and then the printed web may be run directly to the formers of the folder without passing through a circuitous path, or without passing under the folder. Furthermore, various color combinations may be produced by different web runs with the same colors remaining on the plate or form cylinders, or different color combinations may be conveniently produced by employing the same web runs and utilizing different colors on selected form or plate cylinders.

The arrangement provides groups of three printing units, each group including a standard printing unit which may have a pair of reversible printing cylinders, and located in line adjacent the folder, a four-impression printing unit having reversible cylinders and located in line adjacent the standard unit, and another standard unit located in line adjacent the four-impression unit. When more than one folder is employed in line, this arrangement disposes a standard printing unit at each side of the folder, and a four-impression unit intermediate the said standard units. Such arrangement facilitates the threading of the webs through their intended path of travel in the printing machine, and also affords great flexibility in selection of web runs.

With this arrangement, any number of colors up to four may be printed on each side of a web, and alternatively any number of colors may be printed on one side of a web with black on the other, and a simultaneously separate black perfected web may be printed, in each group of three units. Again, the entire four-impression color unit may be used as such, or, if preferred, the lowermost couples thereof may be supplied with black ink and employed for perfecting in black. It is also possible with this arrangement to print in each group of three printing units, two webs, each having three colors on one side, and black on the other. By changing the web run, the same number of webs may be printed with the same number of colors, on each side but with the col-

ors reversed, that is, instead of three colors on the obverse side, and black on the reverse side, the web may be printed with black on the obverse side, and three colors on the reverse side.

It will be understood that the invention may be embodied in other specific forms without departing from the spirit or essential attributes thereof, and it is therefore desired that the present embodiment be considered in all respects as illustrative and not restrictive.

What I claim is:

1. In a printing machine, a folder and a group of three printing units arranged in a line on one floor level, the group including a first printing unit located immediately adjacent the folder and having four cylinders arranged as a standard two-couple perfecting printing unit of the type having its couples longitudinally spaced and each couple including a plate cylinder and a cooperable impression cylinder arranged so that oblique planes passing through the axes of its cylinders intersect above and intermediate its spaced couples, a second printing unit located immediately adjacent the first and having eight cylinders arranged as a lower standard perfecting printing unit similar to the first unit and an upper inverted standard two-couple perfecting printing unit having its couples longitudinally spaced and vertically spaced from the couples of the lower unit, each couple of the upper unit including a plate cylinder and a cooperable impression cylinder arranged so that oblique planes passing through the axes of its cylinders intersect below and intermediate its spaced couples, and a third four-cylinder standard perfecting printing unit similar to the first unit located immediately adjacent the second unit at its opposite side.
2. In a printing machine, a folder and a group of three printing units arranged in a line on one floor level, the group including a first printing unit located immediately adjacent the folder and having four cylinders arranged as a standard two-couple perfecting printing unit of the type having its couples longitudinally spaced and each couple including a plate cylinder and a cooperable impression cylinder arranged so that oblique planes passing through the axes of its cylinders intersect above and intermediate its spaced couples, a second printing unit located immediately adjacent the first and having eight cylinders arranged as a lower standard perfecting printing unit similar to the first unit and an upper inverted standard two-couple perfecting printing unit having its couples longitudinally spaced and vertically spaced from the couples of the lower unit, each couple of the upper unit including a plate cylinder and a cooperable impression cylinder arranged so that oblique planes passing through the axes of its cylinders intersect below and intermediate its spaced couples, and a third four-cylinder standard perfecting printing unit similar to the first unit located immediately adjacent the second unit at its opposite side.
3. In a printing machine, a plurality of folders and a plurality of groups of printing units arranged in a line on one floor level, each group being interposed between adjacent folders and including a first printing unit located immediately adjacent a folder and having four cylinders arranged as a standard two-couple perfecting printing unit of the type having its couples longitudinally spaced and each couple including a plate cylinder and a cooperable impression cyl-

der arranged so that oblique planes passing through the axes of its cylinders intersect above and intermediate its spaced couples, a second printing unit located immediately adjacent the first and having eight cylinders arranged as a lower standard perfecting printing unit similar to the first unit and an upper inverted standard two-couple perfecting printing unit having its couples longitudinally spaced and vertically spaced from the couples of the lower unit, each couple of the upper unit including a plate cylinder and a cooperable impression cylinder arranged so that oblique planes passing through the axes of its cylinders intersect below and intermediate its spaced couples, and a third four-cylinder standard perfecting printing unit similar to the first unit located immediately adjacent the second unit at its opposite side.

4. In a printing machine, a plurality of folders and a plurality of groups of printing units arranged in a line on one floor level, each group being interposed between adjacent folders and including a first printing unit located immediately adjacent a folder and having four cylinders arranged as a standard two-couple perfecting printing unit of the type having its couples longitudinally spaced and each couple including a plate cylinder and a cooperable impression cylinder arranged so that oblique planes passing through the axes of its cylinders intersect above and intermediate its spaced couples, a second printing unit located immediately adjacent the first and having eight cylinders arranged as a lower standard perfecting printing unit similar to the first unit and an upper inverted standard two-couple perfecting printing unit having its couples longitudinally spaced and vertically spaced from the couples of the lower unit, each couple of the upper unit including a plate cylinder and a cooperable impression cylinder arranged so that oblique planes passing through the axes of its cylinders intersect below and intermediate its spaced couples, a third four-cylinder standard perfecting printing unit similar to the first unit located immediately adjacent the second unit at its opposite side, and means for reversibly driving selected cylinders of each printing unit.

5. In a printing machine, a plurality of spaced folders arranged in a line on one floor level, a printing unit located in the line at each side of each folder and having four cylinders arranged as a standard two-couple perfecting printing unit of the type having its couples longitudinally spaced and each couple including a plate cylinder and a cooperable impression cylinder arranged so that oblique planes passing through the axes of its cylinders intersect below and intermediate its spaced couples, and means for reversibly driving selected cylinders of each printing unit.

5 der and a cooperable impression cylinder arranged so that oblique planes passing through the axes of its cylinders intersect above and intermediate its spaced couples, and an eight-cylinder printing unit located in the line between each pair of said perfecting printing units so that two similar perfecting printing units and an eight-cylinder printing unit therebetween forms a group of printing units located in

10 line between adjacent folders, the eight cylinder printing unit having four cylinders arranged as a lower standard perfecting printing unit similar to the perfecting units at each side of the folder and an upper inverted standard two-couple perfecting printing unit having its couples longitudinally spaced and vertically spaced from the couples of the lower unit, each couple of the upper unit including a plate cylinder and a cooperable impression cylinder arranged so that oblique planes passing through the axes of its cylinders intersect below and intermediate its spaced couples.

15 6. In a printing machine, a plurality of spaced folders arranged in a line on one floor level, a printing unit located in the line at each side of each folder and having four cylinders arranged as a standard two-couple perfecting printing unit of the type having its couples longitudinally spaced and each couple including a plate cylinder and a cooperable impression cylinder arranged so that oblique planes passing through the axes of its cylinders intersect above and intermediate its spaced couples, and an eight-cylinder printing unit located in the line between

30 each pair of said perfecting printing units so that two similar perfecting printing units and an eight-cylinder printing unit therebetween forms a group of printing units located in line between adjacent folders, the eight-cylinder printing unit having four cylinders arranged as a lower standard perfecting printing unit similar to the perfecting units at each side of the folder and an upper inverted standard two-couple perfecting printing unit having its couples longitudinally spaced and vertically spaced from the couples of the lower unit, each couple of the upper unit including a plate cylinder and a cooperable impression cylinder arranged so that oblique planes passing through the axes of its cylinders intersect above and intermediate its spaced couples, and an eight-cylinder printing unit located in the line between

35 each pair of said perfecting printing units so that two similar perfecting printing units and an eight-cylinder printing unit therebetween forms a group of printing units located in line between adjacent folders, the eight-cylinder printing unit having four cylinders arranged as a lower standard perfecting printing unit similar to the perfecting units at each side of the folder and an upper inverted standard two-couple perfecting printing unit having its couples longitudinally spaced and vertically spaced from the couples of the lower unit, each couple of the upper unit including a plate cylinder and a cooperable impression cylinder arranged so that oblique planes passing through the axes of its cylinders intersect below and intermediate its spaced couples, and means for reversibly driving selected cylinders of each printing unit.
